(57) **CLAIM**

I claim the ornamental design for a portable deer feeder bracket, as shown and described.

DESCRIPTION

FIG. 1 is a perspective view of the portable deer feeder bracket;

FIG. 2 is a side view of the portable deer feeder bracket;

FIG. 3 is a rear view of the portable deer feeder bracket;

FIG. 4 is a top view of the portable deer feeder bracket; and, FIG. 5 is a bottom view of the portable deer feeder bracket. The broken lines showing the attachment straps, the pulley, and the bucket style feeder, are for the purpose of illustrating environmental structure and unclaimed subject matter, and therefore form no part of the claimed design.
